UNITED STATES PATENT OFFICE.

JOHN REICHERT, OF RACINE, WISCONSIN.

TRACE-CARRIER.

SPECIFICATION forming part of Letters Patent No. 783,892, dated February 28, 1905.

Application filed May 24, 1904. Serial No. 209,532.

To all whom it may concern:

Be it known that I, JOHN REICHERT, a citizen of the United States, residing at Racine, Racine county, State of Wisconsin, have invented 5 certain new and useful Improvements in Trace-Carriers; and I do hereby declare the following to be a full, clear, and exact description of the invention, such as will enable others skilled in the art to which it appertains to make and 10 use the same.

This invention relates to certain improvements in buckles, and more particularly relates to improvements in trace-carriers; and the objects and nature of my invention will 15 be readily understood by those skilled in the art in the light of the following description of the construction illustrated by the accompanying drawings.

An object of the invention is to so form the 20 trace-carrier buckle and hook as to permit easy and economical casting thereof without employing the objectionable coring process in molding and casting, and also whereby the buckle can be easily attached to and removed 25 from the strap—for instance, the hip-strap—without first severing said strap or applying a new peculiarly-constructed strap, and also whereby metal cross-bars of the buckle will 30 be held by the strap from injurious contact with the skin of the animal, and also whereby the hook-bill end will so forcibly engage the strap as to deflect the same inwardly toward 35 the animal, and thereby maintain perfect closure of the hook and prevent tail-hairs of the animal catching under the end of the hook-bill.

With these and other objects in view the invention consists in certain novel features in construction and arrangement, as more fully and particularly pointed out and set forth 40 hereinafter.

Referring to the accompanying drawings, Figure 1 is a perspective view showing a hip-strap having my improved device applied thereto and supporting the trace end. Fig. 45 2 is an edge view or elevation of the trace-carrier and strap therein, showing the positions the strap is forced to assume by reason of the peculiar formation of my improved de-

vice. Fig. 3 is a longitudinal section through the strap and trace-carrier. Fig. 4 is a top 50 plan view of the trace-carrier detached. Fig. 5 is an edge view corresponding to Fig. 2, but showing the hooked finger modified in shape to form a flat-rein guide as well as a trace-carrier.

In the drawings, *a* is a strap—for instance, the hip-strap—and *b* is the trace, having the end cockeye *c*.

My improved device comprises a rectangular buckle having a rigid hook-bill projecting 60 from the upper end cross-bar thereof, the buckle and hook being formed in one piece.

d represents the two longitudinal parallel side bars of the buckle, preferably having the flat inner faces and preferably longitudinally 65 curved or convexed outwardly between their ends, about as shown, so that the inner longitudinal edges of said side bars are longitudinally concaved and the corresponding outer edges longitudinally convexed.

e is a top lower-end cross-bar between the lower ends of the side bars, and *f* is a top upper-end cross-bar between the upper extremities of said side bars. The flat under faces of these cross-bars are elevated above 75 the lower or inner longitudinal edges of the side bars, so that the side edges of the strap at the ends of the side bars fit between and engage the inner faces of the side bars and the outer flat face of the strap extends transversely across the flat inner faces of said cross-bars. These flat inner faces of the end cross-bars are also preferably transversely inclined from their inner edges downwardly and outwardly to their outer edges to generally conform to the angle assumed by the strap in the buckle and by reason of the formation of the parts of my device.

g is an intermediate depressed cross-bar between the inner portions of the side bars and 80 preferably located midway between the ends of the side bars. This center depressed cross-bar is preferably formed with a flat outer face to fit transversely across the flat under face of the strap, and said flat outer face of this 85 cross-bar is depressed below the outer edges

of the side bars, so that the inner side faces of the side bars form edge stops or guides for the strap and whereby the flat outer face of the strap can lie approximately flush with 5 the outer edges of the side bars. This depressed cross-bar is formed with a central rigid outwardly-projecting stud or pin, as shown, to enter a perforation in the strap for the purpose of removably securing the device at the 10 desired location on the strap.

It will be observed that the buckle is entirely open between the side bars and various cross-bars and is also open below the end cross-bars and above the center cross-bar, 15 whereby the device can be easily and economically cast with its hook, hereinafter referred to, without the necessity of coring in preparing molds and in casting.

h is a curved U-shaped finger having one 20 leg of greater length than the other, or what is preferably termed a "hook" or "hook-shaped" finger, having the inwardly-elongated free end, said hook projecting from the outer surface of the upper cross-bar f at a point 25 midway between the side bars. This hook or finger projects outwardly and upwardly from the cross-bar and curves upwardly and inwardly, with its elongated free end inclined inwardly and upwardly and projecting in- 30 wardly beyond the longitudinal plane of the buckle. The inner free end of the hook is comparatively small for the purpose of indenting or pressing into the strap, as herein-after set forth.

35 The device can be easily applied by being slipped onto the strap at a free end thereof and moved to the desired place on the strap, when the strap is drawn taut through the buckle, so that the stud enters the perforation 40 in the strap and the strap extends under the end cross-bars and across the center cross-bar and extends upwardly beneath the free end of the hook.

The elongated free end of the hook engages 45 the strap a distance above the upper-end cross-bar and forces the strap and causes the same to assume such a position that the metal parts of the buckle exposed at the under side thereof are held from engagement with the skin of 50 the animal. The shape of the device is such that the strap in tending to straighten out under the weight or strain of attached parts will bear outwardly against the free end of the hook, whereby the strap will bend in beneath 55 said hook end and beneath the lower-end cross-bar e and will be deflected or bent outwardly between these two points, thereby removing the inner edges of the buckle side bars and the center cross-bar from injurious 60 rubbing contact with the skin of the animal, so that the inner faces of said two inward bends of the strap form the bearing-points engaging the animal. This desired and im- portant point is gained by reason of the lon-

gitudinal curve of the buckle side bars, but 65 mainly and essentially by the elongated free end of the hook.

The hook, in connection with the strap, forms an eye or loop to receive the cockeye of the trace or to receive lines or reins, and the forcible engagement of the hook end against the strap provides an effective closure of the hook, particularly as said hook end indents or bites into the strap forming a depression which, in connection with the shape of the hook, prevents the tail-hairs of the animal catching under the hook end. The shape of the hook is such that the cockeye or other member can be readily and easily slipped under the hook on bending up the strap, and yet such eye or other member will be held in the hook against accidental displacement by reason of the peculiar shape of the device and the forcible impingement of the hook end against the strap. 75 80 85

The hook can be formed comparatively light, as it performs no function in securing the device to the strap, and the device can be easily adjusted on or removed from the strap, as the strap is entirely exposed both above and below the buckle, except for the narrow 90 cross-bars.

The device can be used on various parts of a harness—for instance, as a line-guard and rein-guard as well as a trace-carrier.

In Fig. 5 I show the buckle with U-shaped 95 or hooked finger h' , somewhat elongated or modified in shape to receive a flat rein and form a rein-guide as well as a trace-carrier, but to cause bending of the strap and perform the functions of the hook h . 100

Various modifications in shape and formation might be resorted to without departing from the spirit and scope of my invention as defined by the claims. Hence I do not wish to limit myself to the exact constructions shown. 105

What I claim is—

1. A trace-carrier comprising a longitudinally and outwardly convexed attaching-buckle having the U-shaped finger or hook rigid therewith and projecting longitudinally 110 from an end thereof with its inclined elongated free end projecting inwardly beyond the longitudinal plane of the buckle and at its free extremity formed to forcibly engage and press into the strap, whereby the metal parts of the 115 buckle are held against engagement with the animal.

2. A trace-carrier comprising side bars, a depressed intermediate cross-bar having strap-attaching means, strap-depressing top end 120 cross-bars having inclined under strap-engaging faces, and an approximately U-shaped finger rigid with and projecting from an end cross-bar and having its strap-engaging free end projecting inwardly beyond the longitudinal plane of said side bars, for the purposes 125 substantially as described.

3. A buckle comprising the longitudinal

side bars, end cross-bars, an intermediate depressed cross-bar having a strap-attaching stud, and an approximately U-shaped finger projecting longitudinally from an end cross-bar with its free end projected inwardly beyond the longitudinal plane of said side bars and formed to forcibly engage and depress the strap inwardly; whereby the buckle is held

from engagement with the animal, substantially as described.

In testimony whereof I affix my signature in presence of two witnesses.

JOHN REICHERT.
